UNITED STATES PATENT OFFICE.

WALTER TURTON, OF ARLINGTON, NEW JERSEY, ASSIGNOR TO EVANS H. EASTWOOD, CHARLES W. PARK, AND EDWARD SICKLES, COPARTNERS TRADING AS EASTWOOD AND PARK, OF NEWARK, NEW JERSEY.

DESIGN FOR A BACK FOR MIRRORS, BRUSHES, OR SIMILAR ARTICLES.

SPECIFICATION forming part of Design No. 35,993, dated August 12, 1902.

Application filed June 24, 1902. Serial No. 113,041. Term of patent 7 years.

To all whom it may concern:

Be it known that I, WALTER TURTON, a subject of the King of Great Britain, residing at Arlington, in the county of Hudson and State of New Jersey, have invented and produced a new, original, and ornamental Design for Backs for Mirrors, Brushes, or Similar Articles, of which the following is a specification, reference being had to the accompanying drawing, forming part thereof and being a view of the back of an article having an integral body and handle, as a mirror or brush, showing my new design.

My design relates to the ornamentation of backs of mirrors, brushes, or similar articles.

The leading or characteristic features thereof consist in a body portion having thereon a centrally-arranged representation of a human head, a cluster of flowers arranged below the head and covering the lower section of the body portion, and a cluster of flowers arranged around the upper portion of the head; also, in a handle portion having a series of flowers arranged at intervals thereon and connected by a continuous vine which extends through the floral ornamentations of the body portion.

In the drawing, *a* indicates the body portion; *b*, the handle portion, forming an integral part thereof; *c*, the centrally-arranged representation of a human head on the body portion; *d*, the cluster of flowers arranged below the head; *d'*, the cluster of flowers arranged above the head; *d²*, the series of flowers arranged at intervals on the handle portion, and *d³* the continuous vine extending over the body and handle portions and connecting the floral ornamentations.

The head *c* is provided with flowing hair *e*, which is intertwined among the vine and floral ornamentations.

Having thus described my invention, what I claim, and desire to secure by Letters Patent, is—

The ornamental design for a back for mirrors, brushes or similar articles, substantially as herein shown and described.

In testimony whereof I affix my signature in the presence of two witnesses.

WALTER TURTON.
